UNITED STATES PATENT OFFICE.

WILLIAM FRANKLIN COLE, OF WACO, TEXAS.

PROJECTILE.

SPECIFICATION forming part of Letters Patent No. 671,877, dated April 9, 1901.

Application filed October 13, 1900. Serial No. 32,953. (No model.)

To all whom it may concern:

Be it known that I, WILLIAM FRANKLIN COLE, residing at Waco, in the county of McLennan and State of Texas, have invented a new and useful Improvement in Projectiles, of which the following is a specification.

It is the object of my invention to provide an improved projectile for guns and ordnance of various classes and bores. It is adapted 10 to be used only in a gun having an elliptical bore, since this form has advantages which are of much importance—that is to say, such guns, being practically smooth bores, their “life” or durability is much greater than that 15 of rifled guns, yet they have the same advantage as the latter in respect to imparting rotation to the projectile, whereby a flat trajectory is obtained.

My projectile is elliptical in cross-section 20 throughout the length of its body and is also twisted to conform to the bore of the gun. The front portion of the body is likewise tapered toward the point, which is constructed with a thin edge having a twist or reverse 25 curve. With this form of projectile the rapidity of rotation is maintained and even increased in flight, while the resistance and friction of the air is reduced to a minimum. The result is a high velocity, great range, and 30 accuracy of flight.

In the accompanying drawings, Figure 1 is a side view of my improved projectile. Fig. 2 is a plan or top view. Fig. 3 is a cross-section on line 3 3 of Fig. 1. Fig. 4 is a cross-section on line 4 4, Fig. 1. Fig. 5 is a front end view. Fig. 6 is a view of the side opposite that shown in Fig. 1.

The chief characteristics of form or shape of my projectile are as follows: The body 40 of the projectile is elliptical in cross-section throughout its length and also slightly twisted. The major and minor axes of the ellipse are the same or uniform in the base portion *a*, while they are gradually shortened in the 45 front portion *b*, since the latter is tapered on all sides. Thus the projectile may be considered as having one general characteristic—namely, ellipticity and a uniform twist—and is additionally distinguished by difference of 50 the ellipse in the body portion *a* *b*, while the point *c* is likewise twisted, corresponding to the special shape of said body. The details

are as follows: In the base *a*, which may be considered as including one-half of the length of the projectile, the major and minor axes 55 of the ellipse remain the same throughout, but the front portion *b*, which is included between the base *a* and point *c*, is tapered throughout, so that the major and minor axes are gradually shortened. Thus the major 60 axis of the ellipse is gradually inclined more and more from the base end to the point, as illustrated by shade-lines and also by the line *d*, representing the major axis in Fig. 4. The point *c* has the general form of a wedge or 65 drill point, its broad sides forming obtuse angles with the broadsides of front part *b*, as shown. The said wedge-point *c* is, however, irregular, its thin edge having a reverse or S-shaped curve (see Fig. 5) and its broad 70 sides being so beveled as to impart a twist corresponding to that of the body *a* *b* of the projectile. This shape of the point and the taper of the front portion enable the projectile to cleave or penetrate the air with minimum 75 friction and resistance, besides maintaining and even increasing for a time the rotation of the projectile. Thus great accuracy, high velocity, and a very flat trajectory are obtained with a given charge of explosive. 80

It is to be understood that the uniform elliptical and twisted portion *a* of the projectile will duly fit the elliptical and twisted bore of the gun, (not shown,) and thus serve to guide the projectile when being discharged; 85 but the irregularly-elliptical front portion *b*, owing to its taper, will not come in contact with the sides of the bore.

Having thus described my invention, what I claim, and desire to secure by Letters Patent, is—

As an improved article of manufacture, the herein-described projectile for smooth-bore guns, whose body is twisted spirally, and also elliptical in cross-section, throughout its 95 length, the major and minor axes of all cross-sections of the base portion *a*, being uniform in length, and the front portion *b* tapered, and the point *c* having a twist or reverse curve, as shown and described.

WILLIAM FRANKLIN COLE.
